CLAIM

The ornamental design for a razor cartridge, as shown and described.

DESCRIPTION

FIG. 1 is a perspective view of a design of a razor cartridge of the present invention;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken lines illustrate portions of the razor cartridge and form no part of the claimed design.
